[57] CLAIM

The ornamental design for an X-ray viewer, as shown and described.

DESCRIPTION

FIG. 1 is a front perspective view of an X-ray viewer, showing our new design;

FIG. 2 is a front elevational view thereof;

FIG. 3 is a rear perspective view thereof;

FIG. 4 is a bottom plan view thereof;

FIG. 5 is a left side elevational view thereof.

The conventional electrical cord has been shown broken away in FIG. 3 for ease of illustration and to indicate indeterminate length.

FIG. 1

FIG. 2

FIG. 3

FIG. 4

FIG. 5
